UNLOADER FOR SLEEVE VALVE GAS COMPRESSORS

Christopher Broom Smith, Naphill, England, assignor to Broom and Wade Limited, High Wycombe, England, a British company

Application May 31, 1946, Serial No. 673,592
In Great Britain June 4, 1945

8 Claims. (Cl. 230—22)

1

This invention relates to reciprocating compressors for air or gas of the type having a sleeve valve controlling the admission of air to the cylinder from a suction chamber and its delivery to an intermediate delivery chamber from which the air passes through a non-return valve to the outlet of the compressor. It has been proposed to provide a compressor of this type with a port in its cylinder head which communicates with the atmosphere and is controlled by a valve which normally closes the port but is open to place the cylinder in communication with the atmosphere and unload the compressor.

According to the present invention an air or gas compressor of the above type is provided with a passage extending from the intermediate delivery chamber (delivery to which is controlled by the sleeve valve) to the atmosphere or to the suction chamber and with an unloading valve arranged to open or close that passage.

The invention is particularly applicable to compressors in which one end of the sleeve valve reciprocates in an annular space between the cylinder and an inwardly-projecting part of the cylinder head. The intermediate delivery chamber may be constituted by the portion of this annular space beyond the end of the sleeve valve.

The invention will now be described, by way of example, as applied to a reciprocating compressor, and with reference to the accompanying drawings in which:

Figure 1 is a vertical section through a cylinder and associated parts of one form of compressor in accordance with the invention;

Figure 2 is a section upon the line 2—2 of Figure 1 looking in the direction of the arrows;

Figure 3 is an elevation with parts broken away to show the internal construction of a second form of compressor; and

Figure 4 is a plan of the compressor shown in Figure 3 with a cylinder head removed.

Referring first to the construction shown in Figures 1 and 2, the compressor comprises a cylinder 11 which is surrounded by a suction chamber 12 communicating with the cylinder by an annular port or series of ports 13. The air inlet to the suction chamber is indicated at 14 and water-jacket space around the cylinder at 15, 16.

Within the cylinder there reciprocates a sleeve valve 17 and inside the sleeve valve a piston 18 operated by a connection rod 19, the crank, crankcase and lower portion of the cylinder being omitted in the drawing as the construction of these parts is well understood. On the top of the cylinder there rests an intermediate head

2

plate 20 and above the head plate 20 a main cylinder head 21, the head plate 20 and the main head 21 together constituting the cylinder head and being secured by studs 22 and nuts 23. To the underside of the intermediate head plate 20 there is secured an inwardly-projecting part 24 of the cylinder head, the part 24 being secured to the intermediate plate 20 by screws 25 and the whole of the three parts of the head, 20, 21, 24, being secured together by studs 26 and nuts 27. The portion 24 of the cylinder head which projects inwardly into the cylinder provides an annular space 28 between itself and the inner wall of the cylinder 11 which fits the upper end of the sleeve valve 17 and in which the upper end is able to reciprocate. A suitable internal sealing ring 29 is provided in the top of the sleeve valve 17 to afford the tight joint between it and the cylinder head portion 24. This portion 24 is formed with spaced passageways 30, formed by short flutes in its external surface at intervals around its lower edge, which passageways are always open to the cylinder but are covered by the sleeve valve 17, which is raised during the suction stroke, so that throughout this stroke the intermediate delivery chamber 28 is cut off from communication with the cylinder.

During the delivery stroke the sleeve valve 17 is lowered and uncovers the communication of the passageways 30 with the intermediate delivery chamber 28 so that the piston 18 may, during the delivery stroke, force the air through the passages into the intermediate delivery chamber 28.

The intermediate head plate 20 is formed with an annular space 31 in its under surface which constitutes a continuation of the intermediate delivery chamber 28 and this space communicates through a ring of ports 32 with the upper face of the intermediate head plate 20 where it lies within a large outlet port 33 formed within the main head casting 21. The upper ends of the ring of ports 32 are closed by an annular plate valve 34 which seats on the upper surface of the intermediate head plate 20 above the ports 32 and is urged downwardly by springs 35 held in recesses in a ring-shaped casting 36 which overlies but is spaced from the plate valve 34. The ring-shaped casting 36 is supported from the intermediate head plate 20 by lugs 37 which project from its underside and rest on the plate 20, these lugs being pierced by holes through which pass fixing studs 38. The normal delivery of the compressor thus passes through the plate valve 34 into the outlet 33 and the annular de-

livery chamber 28 does not constitute any dead air space in the compressor because after it has closed the communication of the space above the piston 18 with the intermediate delivery chamber through the passages 30 at the end of the delivery stroke, the sleeve valve 17 continues to move upwardly and forces air out of the intermediate delivery chamber 28 through the valve 32 until the sleeve valve has reached the top of the space afforded by the intermediate delivery chamber. When the valve 17 is near the top of its stroke it opens communication between the suction chamber 12 and the interior of the cylinder owing to the ring of ports 39 in the sleeve valve coming into register with the inlet ports 13 in the cylinder wall.

The intermediate head plate 20 is also provided with a passage 40 which leads out of the intermediate delivery chamber at 31 to one side of the cylinder to a position where it comes beneath an unloading port 41 formed in the main head casting 21. The unloading port 41 is closed by an inverted lift-valve 42 which constitutes an unloading valve and is provided with a stem extending upwardly through the cylinder head into a control cylinder 43. In the control cylinder 43 is a control piston 44 which bears upon the stem of the unloading valve 42 and the piston and valve tend to be lifted by a spring 45.

The control cylinder 43 is connected by a pipe 46 to an automatic pilot valve, not shown in the drawing. The pilot valve is connected to the air receiver to which the compressor delivers, or to some part connected therewith, and it admits pressure to the pipe 46 when the desired working pressure is reached. When air is admitted to the pipe 46 it causes the control piston to move down to open the valve 42 and places the passage 43 in communication, through the port 41, with a further portion 47 of the passage which extends from the intermediate delivery chamber at 31.

As can be seen from Figure 2 of the drawing, the passage 47 communicates with a port 48 in the lower face of the head 21 and thence by way of a port 49 in the intermediate head plate 20 and a passage 50 in the cylinder, which constitutes an extension of the passage 43, with the suction chamber 12.

In the operation of the unloading device, when the valve 42 is closed compressed air is delivered to the outlet 33 through the plate valve 34 and builds up pressure, in the receiver or other vessel, to which the compressor delivers. When the air pressure has been built up to the predetermined value, the pilot valve operates and delivers air under pressure to the pipe 46, thus causing the valve 42 to be opened. When the valve is opened the air delivered by the piston to the intermediate delivery chamber 28 passes from the intermediate delivery chamber by way of the passage 40, port 41 and further extensions of the passages 47 and 50, to the suction chamber 12. Return of air past the valve 42 is prevented because on the suction stroke of the compressor the communication between the intermediate delivery chamber 28 and the cylinder is cut off by the sleeve valve 17 and therefore all the air passing into the cylinder enters it through the ports 13. After the sleeve valve 17 has cut off the intermediate delivery chamber from the cylinder it continues to rise and delivers air through the unloading port 41 to the suction chamber 12. In the suction belt 12 the relatively hot air which has been expelled from the cylinder and to the intermediate delivery chamber becomes mixed

with atmospheric air from the inlet 14 and cooled before it is drawn again into the cylinder and redelivered through the unloading valve.

Two results follow from this arrangement of the unloading port, namely, first that as hot air is not sucked to and fro past the valve on both suction and delivery strokes of the piston, the valve is not subjected to so much heating as in the case where the valve opens a direct communication between the cylinder and the suction zone. The risk of the valve reaching a high temperature and causing carbonization of the oil is therefore reduced. Secondly, as the intermediate delivery chamber 28 is interposed between the cylinder and the unloading passages and the direction of air flow is always the same through these parts, and as also after the piston has been shut off from the intermediate delivery chamber the sleeve valve continues to deliver some air, there is less noise from the operation of the unloader than has previously been the case.

Furthermore, as the valve 42 does not lie over the cylinder or directly communicate with it there is no risk of any damage being done should the head of the valve break or the spring 45 break, while the compressor is in operation. With the prior construction it would have been possible for the valve head in these circumstances to fall into the compressor cylinder, or at least 30 to come in contact with the head of the piston, and cause damage.

Referring to Figures 3 and 4, these show a two-cylinder compressor comprising cylinders 60, 61, which contain sleeve valves 62, 63 and pistons 64, 65. The cylinders are in a single block surrounded by a waterjacket space 66 and surrounded by an intermediate head plate 67 and a main head casting 68. There is a suction chamber 69 and air inlet 70, the general arrangement of all these parts being similar to that already described in connection with Figures 1 and 2. However, the construction differs in that the unloading port 71 instead of being located in the head as in the case of the unloading port 41 of Figures 1 and 2 is located in the cylinder block and the lift valve 72 which controls it has a stem which extends downwardly through a guide 73 into a chamber 74 at the side of the cylinder block. The chamber 74 constitutes a passage which connects the unloading port with the suction chamber 69. The valve 72 is urged in a direction to close the port 71 by a spring 75.

As can be seen from the plan of Figure 4, there are two valves 72, one for each cylinder, and the two valves are operated by a single lever 76 having a forked end at 77, 78, the two arms of the fork engaging the lower ends of the stems of the valves. The forked lever 76 is pivoted on a bracket 79 secured to the exterior of the cylinder block and the lever passes to the outside of the cylinder block through a large aperture in the side thereof which aperture is covered by a casing 80. The casing 80 embodies in its upper portion an actuating cylinder 81 which contains a piston 82 and is connected to an air-supply pipe 83, corresponding to the pipe 46 of Figure 1. The space 84 in the intermediate head plate 67, which corresponds to the passage 40 of Figure 1, is shaped so as to extend into the intermediate delivery chamber of each cylinder, as indicated by the chain lines 85 of Figure 4. It will be appreciated that the sectioned part of Figure 3 is taken upon an irregular plane which is approximately represented by the line 3-3 of Figure 4. The operation is the same as in the case of

Figures 1 and 2, in this instance both cylinders being unloaded simultaneously by operation of the same lever.

Although a piston and cylinder have been shown in the drawings for operating the valves which control the unloading ports, it will be appreciated that a screw or cam or other mechanical device could be employed for operating the valve either in addition to the piston or alternately thereto. The mechanical operation of the unloading device may be of service in cases where it is desired to start up the compressor and connect it by hand to a system of pipe work which is already under pressure, as where there are several compressors connected to supply a single system.

I claim:

1. A compressor comprising, in combination, a cylinder, a sleeve valve reciprocable therein, a piston reciprocable within the sleeve valve, means for operating the sleeve valve and piston, a suction chamber in the form of an annular zone around the cylinder communicating with the cylinder through ports controlled by the sleeve valve, an intermediate delivery chamber communicating by ports controlled by the sleeve valve with the cylinder, an outlet, a delivery valve between the intermediate delivery chamber and the outlet, a passage extending from the intermediate delivery chamber into communication with atmosphere and an unloading valve arranged to open and close that passage.

2. A compressor as claimed in claim 1 wherein the passage extending from the intermediate delivery chamber into communication with atmosphere leads into the suction chamber of the compressor which suction chamber is itself open to atmosphere.

3. A compressor as claimed in claim 1 wherein the cylinder has a cylinder head with an inwardly-projecting portion affording an annular space between the cylinder and said inwardly-projecting portion of the cylinder head, one end of the sleeve valve reciprocates in said space, and the intermediate delivery chamber is constituted by a portion of said annular space beyond the end of the sleeve valve.

4. A compressor as claimed in claim 1, wherein the unloading valve is constituted by a lift valve opening against the flow of air from the intermediate delivery chamber to atmosphere and provided with means for lifting it from its seating against the pressure when unloading is to occur.

5. A compressor as claimed in claim 1, wherein the unloading valve is constituted by a lift valve opening against the flow of air from the intermediate delivery chamber to atmosphere, and wherein means are provided for lifting the un-

loading valve from its seat comprising a cylinder and piston and pipe connections for the supply of operating pressure thereto.

6. A compressor as claimed in claim 1, wherein the cylinder comprises two cast parts, the one a main cylinder-body casting and the other a cast cylinder head, with means to secure the head to the main casting, the unloading valve is a lift valve located in the cylinder head, and the passage which is opened and closed thereby is constituted in part by a passage cast in the cylinder head and in part by a passage in the main cylinder-body casting, the two passage parts communicating by ports formed in the joint between the cylinder head and the main casting.

7. A compressor as claimed in claim 1, wherein the unloading valve is a lift valve mounted on the cylinder of the compressor.

8. A compressor, comprising, in combination, a cylinder block and two cylinders side by side in the block; each cylinder having associated therewith a sleeve valve reciprocable therein, a piston reciprocable within the sleeve valve, means for operating the sleeve valve and piston, a suction chamber in the form of an annular zone around the cylinder communicating with the cylinder through ports controlled by the sleeve valve, an intermediate delivery chamber communicating through ports controlled by the sleeve valve with the cylinder, an outlet, a delivery valve between the intermediate delivery chamber and the outlet, a passage extending from the intermediate delivery chamber into communication with atmosphere, and an unloading valve arranged to open and close that passage; and the two unloading valves are located side by side in the cylinder block and an operating lever engages both unloading valves and is operated by a single actuating means.
